(57) **CLAIM**

The ornamental design for a device for delivering injectable material, as shown and described.

DESCRIPTION

FIG. 1 is a front perspective view of a device for delivering injectable material.

FIG. 2 is a front view of the device illustrated in FIG. 1.

FIG. 3 is a rear view of the device illustrated in FIG. 1.

FIG. 4 is a left side view of the device illustrated in FIG. 1.

FIG. 5 is a right side view of the device illustrated in FIG. 1.

FIG. 6 is a top view of the device illustrated in FIG. 1.

FIG. 7 is a bottom view of the device illustrated in FIG. 1; and,

FIG. 8 is a front perspective view of the device of FIG. 1, shown in an environment of use.

The broken lines illustrate portions of the device forming no part of the claimed design. In FIG. 8, the additional broken lines showing a cartridge assembly coupled to the device illustrate environmental subject matter and form no part of the claimed design.

1 Claim, 8 Drawing Sheets
